UNITED STATES PATENT OFFICE.

CHARLES E. STRATING, OF CHICAGO, ILLINOIS.

WINDOW WEIGHT.

Application filed July 24, 1920. Serial No. 398,739.

To all whom it may concern:

Be it known that I, CHARLES E. STRATING, a citizen of the United States, and a resident of the city of Chicago, county of Cook, 5 and State of Illinois, have invented certain new and useful Improvements in Window Weights, of which the following is a specification.

My invention relates to improvements in 10 window weights, and has for its primary object the production of a weight of such construction as to enable it to be used in combination with both an upper and lower sash.

Another object of my invention is the 15 production of a window weight which facilitates the easy changing of broken sash cords and parts.

Other objects will appear hereinafter. 20 The invention consists in the combinations and arrangements of parts hereinafter described and claimed.

The invention will be best understood 25 by reference to the accompanying drawings forming a part of this specification, and in which,

Fig. 1, is a perspective view illustrating a construction involving my invention,

Fig. 2, is a top plan view of the weight, 30 Fig. 3, is a side view showing a portion broken away,

Fig. 4, is a view at right angles to Fig. 3, showing a portion broken away, and

Fig. 5, is a view of the weight positioned 35 within the weight box of the window frame.

The preferred form of construction of my window weight is a concrete block 1 having a slot 2 moulded in one end, a pulley 3 mounted on a bearing member 4 in said 40 slot 2, said bearing member 4 consisting of a metal pin having a head on one end. The bearing member 4 is adapted to be loosely mounted in a hole which passes through the block and the slot 2. The member 4 is so 45 mounted in the weight as to facilitate the easy removal of said member, thus allowing the removal of the pulley 3 from the slot 2. The above construction is such that a window cable may be easily inserted 50 around the pulley.

Heretofore, double weights and other expensive contrivances have been used to facilitate the raising and lowering of window sashes, however, the construction of the 55 weight herein described, is such that it can be used singly to operate both sashes. The

operation of the weight is as follows: The weight is introduced into a weight box 5 which is so constructed as to allow the weight to move freely upwards and downwards within its confines. At the bottom of said weight box and on the sash side, an opening 6 is provided, said opening permitting easy access to the weight and pulley when the weight is resting upon the bottom of the box. The weight is so positioned within the box as to allow the head of the loosely mounted bearing member 4 to be accessible from the opening 6, thus allowing the withdrawal of said pin, the removal of the pulley, and the changing of a broken sash cable, thus eliminating the usual trouble of tearing out the sides of the weight box in order to gain access to the cable and the weight. 75

A window cable 7 is secured to the upper sash 8, and is then passed over a pulley 9, said pulley 9 being secured within the sash plate 10. The rope is then placed around the pulley 3 in the weight box 1, passing through the pulley 11 which is secured in the sash plate 10 opposite a point 12, said point 12 being the securing position for the opposite end of the rope 7. The weight should be suspended upon as short a cable 85 as possible, its position when the windows are closed being about the center of the weight box, and when the lower sash is raised, the weight should be suspended near the base of the box. 90

Heretofore, it has been necessary to remove the sashes and a portion of the weight box in order to change a broken cable. However, with the construction herein shown, it is only necessary to remove the 95 sashes to repair the broken cable, inasmuch as a new cable may be introduced into the weight box through the pulley holes, then through the pulley in the weight, said weight being accessible through the opening 6, then with a cord or similar means it is drawn up through the other pulley, and both ends are made fast to the sashes as shown in Fig. 1. 100

While I have illustrated and described 105 the preferred form of construction for carrying my invention into effect, this is capable of variations and modifications without departing from the spirit of the invention. I, therefore, do not wish to be limited to the precise details of construction set forth, but desire to avail myself of such 110

variations and modifications as come within the scope of the appended claims.

Having described my invention, what I claim as new and desire to secure by Letters Patent is:—

1. In combination with window sashes and a sash plate; a flexible cable connecting said sashes; a concrete weight provided with a removable pulley mounted on said cable; and an opening in said sash plate affording ready access to said weight for removal of said pulley to renew said cable, substantially as described.

2. In combination with window sashes and a sash plate; a flexible cable connecting

said sashes, a weight provided with a pulley mounted on said cable and in said weight by a removable member; and an opening provided in said sash plate to afford ready access to said weight for withdrawal of said member and pulley to renew said cable, substantially as described. 20

In testimony whereof I have signed my name to this specification in the presence of two subscribing witnesses.

CHARLES E. STRATING.
